UNITED STATES PATENT OFFICE.

DAVID F. FELTON, OF PARSONS, KANSAS, ASSIGNOR TO THE GAS CRUDE OIL BURNER COMPANY, OF MUSKOGEE, OKLAHOMA, A CORPORATION OF OKLAHOMA.

CRUDE-OIL BURNER.

1,158,668.

Specification of Letters Patent.

Patented Nov. 3, 1915.

Application filed February 12, 1915. Serial No. 7,787.

To all whom it may concern:

Be it known that I, DAVID F. FELTON, a citizen of the United States, residing at Parsons, in the county of Labette and State of 5 Kansas, have invented new and useful Improvements in Crude-Oil Burners, of which the following is a specification.

This invention is an improved crude oil burner for use in stoves and furnaces and 10 also adapted for use in locomotives and other types of engines for generating steam.

One object of my invention is to provide an improved burner of this character in which the oil is converted into gas before 15 being consumed.

Another object is to provide an improved burner of this character in which atmospheric air is highly heated before being 20 mixed with the gas generated from the oil, thereby greatly promoting active combustion.

Another object of the invention is to provide an improved burner of this character in which there is a down draft of the mixture 25 of gas and air.

Another object of the invention is to provide an improved burner of this character embodying a generating plate against which the down draft mixture impinges at the instant of ignition and which generating plate prevents the accumulation of and provides for the consumption of carbon.

With the above and other objects in view the invention consists in the construction, 30 combination and arrangement of devices hereinafter described and claimed.

In the accompanying drawings: Figure 1 is a vertical central longitudinal sectional view of an oil burner constructed in accordance with my invention. Fig. 2 is a detail horizontal sectional view of the same on the plane indicated by the line *a—a* of Fig. 1. Fig. 3 is a similar view of the same on the plane indicated by the line *b—b* of Fig. 1. Fig. 4 is a vertical central sectional view of a modified form of my invention especially adapted for use in a range, cook stove or furnace.

Referring first to the form of my invention shown in Fig. 1 a hollow base 1 is provided which is adapted to be placed on the grate in a stove and is open at its lower side so that air from below the grate may be caused to pass upwardly therethrough.

This base may be of any suitable form and 55 size and is provided at its rear end with an upwardly extending tubular portion 2, at the upper end of which is an upwardly extending inner annular flange 3 and an outwardly extending outer substantially horizontal annular flange 4. An air heating tube 5 is also provided which is curved as shown so as to form an ascending intake arm 6 and a downwardly extending discharge arm 7. This tube is preferably and is here 60 shown as a single casting and is provided at the lower end of its intake arm with an annular groove 8 to receive the upper edge of the tubular portion 2 of the base and to bear against the inner side of the flange 3, 65 and has also an outwardly extending flange 9 to bear on the flange 4. Hence a joint is formed between the tubes 2 and 5 and the tube 5 is secured in place by means of suitable rivets of bolts 10.

An oil supply pipe 11 extends through the upper portion 2 of the base and is arranged in the center of the intake arm 6 of the tube 5. A curved tubular generating member 12, which is of greater diameter than the pipe 80 11 is arranged in the center of the down-turned arm 7 of said tube 5 and is connected to the pipe 11 by means of a reducer coupling 13. A jet member 14 has a downwardly contracting wall which is threaded 85 to the lower end of the generating or jet member 12 as at 15. The tubular lower portion of the jet member is fitted in and projects downwardly through a central opening in a mixing plate 16, the said mixing plate 90 being fitted in the lower end of the arm 7 of the tube 5 and being provided with radial segmental openings 17 as shown. At the lower end of the tubular arm 7 is an outwardly extending annular flange 18. A 95 tubular mixing member 19 has its lower end choked or contracted as at 20 and is provided at its upper end with an annular flange 21 to bear on the lower end of the tubular arm 7 and with an outwardly extending annular flange 22 to bear under the flange 18. Thereby a joint is formed between the tubular arm 7 and said mixing member 19. Said arm and member are secured together by bolts or rivets 23. A 100 generating plate which is also a deflector 24 is detachably fitted on a supporting bracket 25 and is arranged at a suitable

distance below the choked lower end 20 of the mixing member 19. This bracket 25 has a supporting arm 26 that extends from the tubular portion 2 of the base and also 5 has an inclined brace 27 that bears on the upper side of the base. The generating plate 24 is dish-shaped cross sectionally, being thereby provided with an upwardly and outwardly extending deflecting wall 28 and 10 the central portion of the bottom of said plate is conical in form as at 29 so that its apex forms what I term a firing pin 30 which is arranged directly under the center of the mixing tube or element 19.

15 The operation of my improved burner is as follows: Initially the burner must be heated, which may be done by burning a small quantity of oil in the generating plate 24. When the burner has been heated to the 20 required degree oil is then caused to be supplied through the pipe 11. This oil becomes vaporized and is converted into gas in the vaporizing element 12 and issues as a highly combustible gas through the jet opening 14. Air is drawn up through the base and 25 the tubular portion 2 thereof into the tube 5 and this tube, being highly heated superheats the air and forces it in a down draft through the arm 7 and the openings 17 30 of the mixing plate into the mixing tube 19 where it becomes commingled with the gas and forms a highly combustible mixture which strikes against and is deflected by the generating plate 24 and is ignited as it issues 35 from said mixing element 19. The deflecting plate deflects the flame from the burner outwardly in all directions and causes the flame to impinge against the tube 5 so that the latter is maintained in a highly heated 40 condition, especially at its down draft discharge portion 7 and in which the vaporizing element 12 is located. Hence the vaporizing element is also kept very highly heated and the gas and air are in a highly heated 45 condition when they are mixed in the mixing element and thereby the mixture is caused to burn in a clear flame and with practically no smoke. Such carbon particles as are carried by the mixture are arrested by 50 and accumulated on the firing pin 30 which forms the apex of the central cone in the generating plate and this carbon is held in direct contact with the flame and subjected to the action thereof so that it is almost entirely consumed. From time to time, at long 55 intervals when carbon has accumulated on the firing pin, the generating plate should be removed from the bracket 25, which may be readily done, and the carbon deposit 60 knocked off from the firing pin by a hammer or other suitable implement. This is practically all the attention the burner requires.

The down draft imparted by my burner to the gas and highly heated air and in the 65 mixing tube or element greatly facilitates

and promotes the mixture of the gas and air and insures the combustion of all of the gases.

In the form of my invention shown in Fig. 4 in which the burner is especially adapted for use in a cook stove, range or furnace the air heating tube 31 is flattened on its upper side and the upper side of the base 32 is provided with an annular recess 33 to receive and hold the bottom of the generating plate 34. Other modifications may also be made in the form proportion and construction of the several parts of my improved burner without departing from the spirit of the invention and within the scope of the appended claims.

Having thus described my invention, I claim:

1. In a burner of the class described an air heating tube having an upwardly extending intake arm and a downwardly directed discharge arm, an oil pipe arranged in said air heating tube and having a vaporizing element in the discharge arm of said air heating tube and terminating in a downwardly directed jet element, an air mixing tube connected to the lower end of the downwardly directed discharge arm of the air heating tube and a deflecting plate arranged below the discharge end of said mixing tube. 85

2. In a burner of the class described an air heating tube having an upwardly extending intake arm and a downwardly directed discharge arm, an oil pipe arranged in said air heating tube and having a vaporizing element in the discharge arm of said air heating tube and terminating in a downwardly directed jet element, an air mixing tube connected to the lower end of the downwardly directed discharge arm of the air 100 heating tube and a deflecting plate arranged below the discharge end of said mixing tube, said mixing tube having a contracted lower, discharge end. 90

3. In a burner of the class described an air heating tube having an upwardly extending intake arm and a downwardly directed discharge arm, an oil pipe arranged in said air heating tube and having a vaporizing element in the discharge arm of said air heating tube and terminating in a downwardly directed jet element, an air mixing tube connected to the lower end of the downwardly directed discharge arm of the air 105 heating tube and a deflecting plate arranged below the discharge end of said mixing tube, said mixing tube having a contracted lower, discharge end, the said generating plate having a conical central portion forming a fire pin arranged under the center of said 110 mixing tube. 95

4. An oil burner of the class described comprising a hollow base open at its lower side, adapted to be placed on the grate in a stove or furnace fire box and also having 115

an upwardly extending tubular portion, a curved air heating tube comprising an upwardly extending intake arm and a downwardly directed air discharge arm, said intake arm being attached to the tubular portion of the base, an oil pipe extending up through the upper portion of the base and in the air heating tube, a tubular vaporizing element arranged in the downturned 5 arm of the air heating tube, forming the discharge nozzle or jet member, a mixing plate at the lower end of the discharge end of the air heating tube, having openings for air and also having a central opening 10 through which said nozzle or jet member extends, a mixing tubular member attached to the lower end of the discharge arm of the air heating tube, a generating plate arranged below the mixing tube and having an outwardly flared wall, and a support for 15 said generating plate.

In testimony whereof I affix my signature in presence of two witnesses.

DAVID F. FELTEN.
